Thorpe Guard ATTORNEYS.

Patented Sept. 13, 1927.

UNITED STATES PATENT OFFICE.

ASA W. FARNEY, OF CLAY COUNTY, MISSOURI.

DIKE OR REVETMENT.

Application filed May 9, 1927. Serial No. 189,913.

This invention relates to dikes or revetments and to a method of making same under conditions encountered in the event of a sudden and material rise in the level 5 of the stream where the work is in progress, my object being to make provision for the prompt completion of the work and thus insure the safety of the structure and protection of land which might otherwise 10 be cut away by erosion or damaged by flood.

Dikes or revetments of the character under consideration, essentially comprise rows of piling driven to firm anchorage in the bed of a stream and suitably braced 15 longitudinally and transversely by connecting timbers, mats woven around the piling to be sunk to the bed of the stream, and screen poles extending through the mats and adapted to collect and hold débris and sand 20 or soil washed against them by the stream. In the construction of such a dike, the mat initially rests on the water and after the screen poles are secured to the mat it is weighted with sufficient rock to sink it to 25 the bed of the stream. In the event of a sudden rise of the water level to a material distance above the mat, before the screen poles are properly secured in position, there is always danger of the loss of or material 30 damage to the mat, and to guard against such catastrophe, it is necessary to immediately effect the sinking of the mat to the bed of the stream. If this is done the work must be suspended, with the probability of 35 loss of material and damage to the land and other property and perhaps endanger life itself, as heretofore no method has been available to securely place the screen poles under the emergency or stream conditions 40 depicted. I have, however, evolved a method and means for disposing the screen poles in operative position under the conditions mentioned, by providing a weighted fascine or bundle of poles or the like, con- 45 taining rocks or other weighty material, and suspending it above or at the water level by wire or equivalent connections along the length of the piling structure and at the upstream side of a row of the piles, and 50 then affixing to it the lower ends of the screen poles, and finally having a row of men simultaneously cut the wires supporting the fascine to permit the latter to sink until it rests upon the mat and against a 55 row of the piling to the upstream side thereof.

Referring now to the drawing for a complete conception of the construction and method of operation, as hereinafter appears, and to the appended claims defining the 60 novelty of the invention and scope of protection sought by patent:

Figure 1 is a fragmentary plan view of a completed dike embodying the invention, it being assumed that the mat is on the bed 65 of a stream and that the fascine and screen poles are in their final or operative position.

Figure 2 is an end view of the same with parts broken away, and the fascine and screen poles properly assembled and supported in elevated position but ready to drop to position on the mat when the supporting wires are cut.

Figure 3 is an enlarged longitudinal section on the line III—III of Figure 2.

In the said drawing, 1 indicates piles driven to a safe anchorage into the bed of a stream to be diked, the piles being arranged in rows A, B and C, the latter being the downstream row. The piling of the different rows are connected by transverse braces 2 and the piling of the longitudinal rows by longitudinal braces 3, the two sets of braces being arranged at proper levels to produce a substantially rigid and skeleton structure, and to further stiffen the structure, the conventional inclined braces 4 are also connected to the piling.

Formed upon and around the piling at the water level is a mat 5 composed of brush, twigs, branches of trees or any other suitable material, and in the event of a sudden and material increase in depth of water which might endanger the work already done, sufficient rock 6 is placed upon the 95 mat to sink it to the bed of the stream as indicated in Figure 2.

Heretofore as suggested, a very sudden and material increase in the depth of the water has made it impossible to set screen 100 poles in operative position, and this is more especially true if the mat has already been sunk in very deep water.

To meet such conditions I provide a suitable fascine 7 or weighted bundle of sticks 105 or the like of the same or greater length than the piling structure, and arrange it at the upstream side of the downstream row of piling so that the water cannot dislodge it, and this fascine or bundle, preferably held together by wiring 8, is suspended by wire loops 9 from the braces nearest to but above

the water line, as shown most clearly by Figure 2.

While the fascine is thus supported, the screen poles 10 are affixed to it at their lower ends, preferably by forcing said ends down through the fascine as shown in Figures 2 and 3. A man for each support then takes a position on the piling structure opposite each of said supports and upon signal all of 5 the supports are cut so that the entire fascine together with the attached screen poles, shall sink until the former rests upon the mat and the lower ends of the screen poles are embedded in or through the latter to aid in the 10 anchorage of the fascine. The final step to effect the completion of the dike, is to connect the upper ends of the screen poles together or in series as indicated at 11 and at the same time fasten the poles of said connection to adjacent braces of the piling structure, it being understood that the tops 15 of the screen poles when the latter are in final or operative position, are preferably at approximately the same level as the tops of the piling. A dike or revetment of this character is relatively inexpensive and yet efficiently serves its purpose, especially in sections of country where the soil is of alluvial character and readily cut by erosive 20 action of streams, especially when the latter are at flood stage and running rapidly.

From the above description it will be apparent that I have evolved a method of and provided a construction of dike for rapid completion in the face of a sudden and great rise in the depth of a stream, and it is to be understood that details of the method and structural features embodied may be varied or modified within the spirit and 30 scope of the appended claims.

What I claim is:

1. The method of producing a dike comprising the driving of a plurality of rows of piling into the bed of a stream, the bracing of the rows of piles by connecting them together crosswise and lengthwise, at different levels, the provision and sinking of a mat around and between the piles, the provision and supporting of a weighted fascine at or 40 above the surface of the stream, the affixing

of the lower ends of a row of screen poles to the fascine, and the freeing of the fascine from its supports, to permit it to sink upon the sunken mat and carry the screen poles with it. 55

2. The method of producing a dike comprising the driving of a plurality of rows of piling into the bed of a stream, the bracing of the rows of piles by connecting them together crosswise and lengthwise, at different levels, the provision and sinking of a mat around and between the piles, the provision and supporting of a weighted fascine at or above the surface of the stream, the affixing of the lower ends of a row of screen 60 poles to the fascine, the freeing of the fascine from its supports, to permit it to sink upon the sunken mat and carry the screen poles with it, and the securing of the upper ends of the screen poles to the piling structure. 65

3. A dike or revetment comprising rows of piling anchored in the bed of a stream, braces connecting the piles firmly together transversely and longitudinally, a mat around and between the poles and upon the bed of the stream, a weighted fascine, a temporary support therefor attached to the piling structure, and screen poles attached at their lower ends to the fascine and movable 70 downward with the latter when the support therefor is removed. 75

4. A dike or revetment comprising rows of piling anchored in the bed of a stream, braces connecting the piles firmly together 80 transversely and longitudinally, a mat around and between the poles and upon the bed of the stream, a weighted fascine, a temporary support therefor attached to the piling structure, screen poles attached at their lower ends to the fascine and movable 85 downward with the latter when the support therefor is removed, and means for fastening the upper ends of the screen poles to the piling structure after the fascine and poles 90 have descended until the former rests upon the mat. 95

In witness whereof I hereunto affix my signature.

ASA W. FARNEY.
